UNITED STATES PATENT OFFICE.

JOHN E. CHATMAN, OF SWAMPSOFT, MASSACHUSETTS.

RADIATOR CONSTRUCTION.

1,187,501.

Specification of Letters Patent. Patented June 20, 1916.

Application filed July 18, 1910. Serial No. 572,425.

To all whom it may concern:

Be it known that I, JOHN E. CHATMAN, a citizen of the United States, residing at Swampscott, in the county of Essex and State of Massachusetts, have invented certain new and useful Improvements in Radiator Constructions, of which the following is a specification, reference being had to the accompanying drawings.

10 This invention relates to improvements in radiator construction and particularly to improvements in radiator constructions which are used in what are called indirect radiator systems; that is, systems in which 15 the radiator-stack is incased and is supported, as from the ceiling, the air being led to and from the casing.

An object of this invention is to provide a radiator construction of this type which 20 may be readily and cheaply installed and the installation of which will cost very much less than in the case of indirect radiator systems now in common use. This low cost of installation is brought about in the following ways, namely: (1) The plates of 25 sheet-metal which form the top, bottom, sides and ends of the casing for the radiator proper or radiator stack may be cut to standard sizes and no time and no stock will 30 be wasted in cutting and fitting these parts; and (2) the steam-fitter may do the work of incasing the radiator-stack and this work of putting up the casing will require much less time than it does by methods heretofore 35 pursued. In the latter methods the casing is built around the radiator-stack by a sheet-iron worker, who first goes to the place of 40 installation to take his measurements and then goes there a second time to build the box of sheet metal around the radiator-stack.

Another object of this invention is to provide a radiator construction of the type hereinbefore mentioned which will prove 45 readily susceptible of repair and the cost of the upkeep of which will be very small. This reduction in the cost of repairs is accomplished in the following manner, namely: (1) The pipe-connections and 50 connections for the hangers by which the structure is supported lie outside of the casing, where they are readily accessible for repair; and (2) the plates forming the top, bottom, ends and sides of the casing may be readily

removed to expose the radiator-stack. All 55 that is necessary to be done to obtain access to the radiator-stack is to slip out one of these readily removable plates; and this plate is just as readily replaced. Of course, any of the casing plates may be so removed 60 and replaced. In my new construction it is not necessary to cut the plates of the casing, in order to fit these plates around the pipe-connections and hanger connections; for, these connections are so placed as 65 to do away with such cutting and fitting.

Briefly described, my new radiator construction comprises a radiator-stack and a casing therefor. The radiator-stack is built up in the usual way but the outside radiator- 70 sections are preferably formed with side-frames cast integral therewith, although the outside radiator-sections may be of the usual pattern or type and the side-frames made 75 separable from them. These side-frames are slotted and grooved to receive the sheet-metal sides, top, bottom and ends of the casing which incloses the radiator-stack and are provided with pipe-connections and hanger-connections which are so located as 80 to avoid the slots and grooves which are formed in the side-frames and in which lie the edges of the sheet-metal casing plates. In addition to the advantages above set forth, my new radiator construction 85 possesses the further advantages of always presenting a workmanlike appearance and also of eliminating poor workmanship; for, these casing plates being cut to size, they are always sure to fit accurately and to provide the proper amount of air-space. 90

In the drawings illustrating the principle of this invention and the best mode now known to me of applying that principle, Figure 1 is an end elevation and Fig. 2 is a 95 side elevation of my new radiator construction, a part of the casing being broken away to disclose the interior; Fig. 3 is a horizontal section on the line A—A of Fig. 2; Fig. 4 is a perspective view of my new radiator 100 construction, a part of the casing being shown broken away; Fig. 5 is a detail in horizontal section which shows on an enlarged scale the construction at one side of the radiator structure; Fig. 6 is a fragmentary detail which shows in perspective the construction of an integral side frame; Figs. 105 7 and 8 are fragmentary details in perspec-

tive of an end member and a top member, respectively, of the casing; Fig 9 is a detail in perspective of a modified form of corner-piece viewed from the inside; Fig. 10 is an 5 end elevation and Fig. 11 is a side elevation of a modified form of my new radiator construction, in which the side-frames are separable from the radiator proper or radiator-stack; Fig. 12 is a section on the line B—B 10 of Fig. 10; Fig. 13 is a fragmentary detail in perspective of one of the detachable side-frames shown in Figs. 10 to 12, inclusive; and Fig. 14 illustrates in horizontal section a modified form of my invention in which 15 an extra long radiator-stack is used.

The radiator-stack or radiator proper consists of the side radiator-sections *a*, *a'* and the intermediate radiator-sections *a''*. These radiator-sections are assembled or 20 connected with one another in the usual way. With the side radiator-sections *a*, *a'* are formed integral the side-frames *b*, *b'* respectively. The side-frame *b* consists of the standards or corner-pieces *c*, the top cross-bar *d* and the bottom cross-bar *e*, which cross-bars connect the upper and lower ends, respectively, of these corner-pieces *c*. Similarly, the side-frame *b'* consists of the standards or corner-pieces *c'*, the top cross-bar *d'* and the bottom cross-bar *e'*, which cross-bars connect the upper and lower ends, respectively, of these corner-pieces *c'*. These corner-pieces *c*, *c'* extend above and below the radiator-stack a distance sufficient to 35 provide the necessary air-space *f* and are formed with lengthwise-extending grooves *g*, *h* in their longitudinal edges. The end wall of each corner-piece is formed near its top and just below the upper cross-bar *d* with a transverse channel or open-ended slot *i* and is further formed near its lower end and just above the lower cross-bar *e* with a similar transverse or horizontal channel *j*. In the side wall of each corner-piece there is 40 a hole *k* through which projects one end of a supporting-bar *m* and a hole *n* through which extends an end of a tie-rod *o*. The tie-rods *o* extend from side to side of the radiator-stack and just above the same, while the 45 supporting-bars *m* lie parallel with the tie-rods *o* and, of course, just below the radiator-stack. In each side wall *c'* of each corner-piece *c* is tapped a hole *p* which is adapted to receive a pipe-connection *q*, whereby 50 provision is made for the inflow and outflow of the circulating fluid (as hot-water, steam, or the like, or in case the apparatus is used for cooling, brine, ammonia, etc.); but both of the pipe-connections *q* may be carried by 55 the same corner-piece *c'*, as is shown in Fig. 4. The end of each supporting bar *m* passes through an eye formed in the lower end of a hanger-bar *r* and this lower end lies between the nuts *s*, *s'* screwed on the projecting 60 end of the supporting-bar *m*. The upper 65

ends of the four hanger bars *r* are fastened to overhead girders or to the ceiling *t* in any suitable way; but it will be understood that any desirable mode of supporting the radiator may be used without departing from the 70 spirit of my invention, the skill of the art being deemed capable of suiting the supporting devices to the exigencies of the circumstances presented by the particular case.

Plates of sheet-metal are used to form a 75 casing for the radiator-stack. The top-plate *u*, the bottom-plate *v* and the end-plates *w* will be made preferably in standard sizes, which will depend upon and vary with the 80 number of radiator-sections used in building up the radiator-stack, of course. As is best shown in Fig. 7, the bottom end-edge or horizontal edge of each end-plate *w* is formed with an inwardly-projecting flange *w*; and as is best shown in Fig. 8, the end 85 edges of the top-plate *u* are formed with downwardly-extending flanges *u'*. In building up the casing, the top-plate *u* is first slipped into the upper slots or recesses *i* in the two corner-pieces of one of the side-frames. The end-plates *w* are next slipped into place in the side-frames with their side-edges or vertical edges sliding in the grooves *g* in the corner-pieces *c*, *c'*. The end-plates *w* overlap at their top edge-portions the 90 downwardly-extending flanges *u'* formed on the top-plate *u*. The bottom plate *v*, which ordinarily has no flanges but is perfectly flat, is next pushed into place in a manner quite similar to the way in which the top-plate *u* was positioned, the corner parts of the bottom plate resting in the lower recesses *j* formed in the lower ends of the corner-pieces *c*, *c'* and its end edge-portions lying 95 below the flanges *w'* formed on the bottom of the end-plates *w*. The side-plates are then pushed into place; but it may be remarked that these side-plates may be put in place at any time and without any regard whatever to the positioning of the 100 other plates *u*, *v*, and *w*. The lower cross-bars *e*, *e'* serve to assist in supporting the bottom plate *v* and the latter in turn assist in supporting the end-plates *w*. The bottom-plate *v* is formed with an opening 105 adapted to receive the discharge end of the cold-air pipe *y*, while the top-plate *u* is formed with a similar opening in which is adapted to fit the intake end of the hot-air pipe *z* (shown only in Fig. 4); but, of course, these pipes may, to suit the requirements of any particular case, be inserted in other plates of the casing, one of the pipes communicating with one of the air-spaces *f* and the other pipe with the other air-space 110 *f*, all in a manner well-known to those skilled in this art.

The upper and lower cross-bars *d*, *e* of the side-frames (Fig. 6) may be dispensed with, if desired, and the outside radiator sections 115

a, a' may be formed with the integral corner-pieces 2 shown in Fig. 9. These corner-pieces may, however, be made separate from, instead of integral with, the outside radiator-sections, as will be perfectly obvious from an inspection of Fig. 9.

Instead of forming the side-frames integral with the outside radiator section (the construction shown in Figs. 1 to 6, inclusive), separable or detachable side-frames 3 (Figs. 10 to 13, inclusive) may be used, if desired. The corner-pieces 4 of the side-frame 3 shown in Fig. 13 are formed with longitudinally-extending grooves 5, 6, in their edges and are joined together by the integral top cross-bar 7, which is L-shaped in transverse section and in the edges of which are grooves 8, 9. The lower ends of the end-walls 4' are connected by the integral lower cross-bar 10 the inner edge of which is grooved, as at 11, and the outer edge of which lies within the inner face of the end wall 4" of the corner-pieces 4, whereby the ready insertion of the side-plates *w* into the open lower ends of the grooves 5 in the side-walls 4" is permitted. The top-plate *u* is pushed from one end into the grooves 8 in the top cross-bars 7 of the side-frames 3 and the end-plates *w* are then forced upwardly into place with their vertical edges sliding in the grooves 6 in the end-walls 4' of the corner-pieces 4. Finally the bottom-plate *v* is pushed into place from one end of the structure, a pair of its edges sliding in the grooves 11 of the lower cross-bars 10 of the side-frames 3. As before the side-plates *w* may be positioned at any time without regard to the other plates.

The corner-pieces 4 may be made separate from each other by merely dispensing with the metal of the cross-bars 7, 10 which join a pair of these corner-pieces to make up a side-frame. By omitting this metal, a corner-piece construction closely resembling that shown in Fig. 9 results. Either one of the cross-bars may be omitted, while retaining the other.

Where the radiator-stack is built up of many sections and is, therefore, extraordinarily long, some of the intermediate sections, as *a'*, may be formed with ribs 12 which are grooved to receive the edges of the end-plates *w*. As shown in Fig. 14, the latter are made up of four parts; but, of course, the number of sections *a'* may be made as great or small as the length of the radiator-stack demands.

In the case in which the side-frames are formed integral with the outside radiator sections, it is to be observed that these integral side-frames are the only parts of the radiator-stack which are exposed to direct contact with the body of air forming the outer atmosphere; and to prevent too rapid radiation and to reduce the radiation loss

of heat from these side-frames, the latter may be lagged with any suitable heat-insulating material.

It is wholly immaterial as to what fluid is passed through the radiator-stack, 70 whether steam, hot water, brine or other heating or cooling liquid or gas. Hence, the arrangement of parts herein shown may, without the exercise of invention, be used with perfectly obvious changes for a system 75 of cooling.

Changes may be made in the details of the radiator construction hereinbefore described, without departing from the spirit of my invention. For example, the casing 80 plates may be made of material other than sheet metal and the walls of the casing may be fastened to the frame-members in ways other than that hereinbefore described (e. g., these walls may be bolted to the frame-members). These changes and all others of a like character are deemed by me to be within the scope of my invention.

I claim:

1. A radiator section or sections provided 90 with corner-pieces at the ends thereof; the ends of said corner-pieces projecting beyond the body portion of the section and being provided with casing-wall-retaining means.

2. A radiator section or sections provided with corner-pieces at the ends thereof; the ends of said corner-pieces projecting beyond the body portion of the section and said corner-pieces being formed with casing-wall-receiving grooves in their longitudinal edges and with transverse casing-wall-receiving grooves in their ends.

3. A radiator including a radiator section; casing - supporting corner - pieces 105 mounted at the ends of the section; the ends of said corner-pieces projecting beyond the body portion of the section and being formed with casing-supporting means; and a tie-bar which connects said corner-pieces 110 and upon which said section rests and is supported.

4. A hollow radiator section formed with a hole and provided with casing-supporting corner-pieces at its ends; the ends of 115 said corner-pieces projecting beyond the body portion of the section and being formed with casing-supporting means and one of said corner-pieces being formed with a pipe-receiving hole for the circulating 120 fluid, the last-named hole communicating with the interior of the section through the first-named hole.

5. A radiator including a radiator section; a pair of casing-supporting corner-pieces the ends of which project beyond the body portion of the section and are formed with casing - supporting means; a tie - bar which connects said corner-pieces and upon which said section rests and is supported; 125

- and supporting devices which engage said tie-bar and support the radiator.
6. A radiator including a hollow radiator section having a hole; casing-supporting corner-pieces mounted at the ends of the section; the ends of said corner-pieces projecting beyond the body-portion of the section and being formed with casing-supporting means and one of said corner-pieces 5 being formed with a pipe-receiving hole for the circulating fluid, the last-named hole communicating with the interior of the section through the first-named hole; and connecting means which connect said corner-pieces and upon which said section rests and is supported.
7. A radiator including a hollow radiator section; a pair of casing-supporting corner-pieces the ends of which project beyond the 10 body portion of the section and are formed with casing-supporting means, one of which is formed with a hole that communicates with the interior of said radiator section and each of which is formed with a hole 15 adapted to receive a cross-bar; a pipe connection fitted in the first-named hole; a cross-bar which extends beneath said radiator section and the ends of which project through the last-named holes; and devices 20 which support the ends of said cross-bar.
8. A radiator section or sections provided with corner-pieces rigidly held thereto; and casing-wall sections adapted to be supported by said corner-pieces.
9. In combination, a plurality of radiator sections one of which is provided with corner-pieces having in its ends transverse grooves, said ends projecting beyond the body portion of said radiator section; and 25 a casing for said radiator sections; the top and bottom of said casing having edge portions which fit in said transverse grooves.
10. In combination, a plurality of radiator sections having corner-pieces provided 30 with transverse grooves in their ends and with grooves in their longitudinal edges, said ends projecting beyond the body portions of said sections; and a casing for the latter; the top and bottom of said casing having edge portions which fit in said transverse 35 grooves and the sides of said casing having edge portions which fit in the grooves formed in the longitudinal edges of said corner-pieces.
11. A structure of the class described, consisting of a plurality of radiator sections having corner-pieces formed with grooves and provided with pipe connections; a casing which surrounds said sections and the edge portions of which fit in said grooves; cross-bars which pass under said radiator sections and through said corner-pieces; and supports for the ends of said cross-bars.
12. A radiator including a radiator- 45 stack; casing-supporting corner-pieces fas- tened thereto; supporting devices which support said radiator-stack and the ends of which are mounted in said corner-pieces; and casing members which incase said radiator-stack and are carried by said corner-pieces; the latter extending beyond the radiator-stack to determine the allowance for air-space and being formed with openings which communicate with the radiator-stack for the ingress and egress of the circulating 50 fluid.
13. A structure of the class described, consisting of a plurality of radiator sections; grooved corner-pieces; a casing which surrounds said sections and the edge portions 55 of which fit in the grooves in said corner-pieces; cross-bars which pass under said sections and through said corner-pieces; and supports for the ends of said cross-bars.
14. A structure of the class described, consisting of a plurality of radiator sections formed with corner-pieces which project beyond the same; casing members which surround said sections and the edge portions 60 of which engage said corner-pieces; cross-bars which pass under said sections and through said corner pieces; and supports for the ends of said cross-bars.
15. A structure of the class described, consisting of a plurality of radiator sections 65 provided with corner-pieces which project beyond the same and are provided with pipe connections that communicate with the radiator sections; casing members which surround said sections and the edge portions 70 of which engage said corner-pieces; and devices for supporting said radiator sections.
16. A structure of the class described, consisting of a plurality of radiator sections; corner-pieces; casing members which surround said sections and the edge portions of which engage said corner-pieces; and devices which support said radiator sections and which engage only said corner-pieces.
17. A hollow radiator section or sections 75 formed with a hole and provided at the ends of the section with casing-supporting corner-pieces which extend beyond the body portion of the section; one of said corner-pieces being formed with an opening that 80 communicates through said hole with the interior of the section and that is adapted to receive a pipe connection.
18. A structure of the class described, consisting of a radiator-stack; frame-members 85 carried by the same; supporting members which support said radiator-stack and are mounted in said frame-members; and casing members which are mounted in the latter and are readily removable therefrom and 90 which incase said radiator-stack.
19. A structure of the class described, consisting of a radiator-stack; frame-members carried by the same; supporting members which support said radiator-stack and are 95

mounted in said frame-members; and casing members which are mounted in the latter and are readily removable therefrom and which incase said radiator-stack; said frame-members being provided with connections for the circulating fluid.

20. The combination with a radiator-stack; of frame-members which are arranged around opposite end sections of the same; supports for said radiator-stack which are carried by said frame-members; and casing members which incase said radiator-stack and are removably mounted in said frame-members; the latter being provided with connections for the circulating fluid.

21. The combination with a radiator-stack; of frame-members carried by the same; tie-members for binding the latter together; casing members which incase said radiator-stack and are mounted in said frame-members; supporting members carried by said frame-members for supporting said radiator-stack; and connections in said frame-members for the circulating fluid.

25. 22. A structure of the class described, consisting of a plurality of radiator sections forming a radiator-stack the end sections of which are provided with grooved corner-pieces formed with openings for the admission and outlet of the circulatory fluid to and from said sections; and casing members carried by said corner-pieces and mounted in the grooves thereof; two of said casing members being formed with openings for the admission and outlet of the air the temperature of which is to be changed.

23. A structure of the class described, consisting of a plurality of radiator sections forming a radiator-stack the end sections of which are provided with corner-pieces formed with openings for the admission and outlet of the circulatory fluid to and from said sections; casing-members carried by said corner-pieces, two of said casing members being formed with openings for the

admission and outlet of the air the temperature of which is to be changed; and bars which support the radiator sections and the ends of which are supported in said corner-pieces.

50

24. A structure of the class described, consisting of a plurality of radiator sections forming a radiator-stack the end sections of which are provided with corner-pieces formed with openings for the admission and outlet of the circulatory fluid to and from said sections; casing-members carried by said corner-pieces and formed with openings for the admission and outlet of the air the temperature of which is to be changed; bars which support the radiator sections and the ends of which project outside of said corner-pieces; and supporting members the ends of which are connected with and support the projecting ends of said bars.

65

25. A structure of the class described, consisting of a plurality of radiator sections forming a radiator-stack the end sections of which are provided with grooved corner-pieces formed with openings for the admission and outlet of the circulatory fluid to and from said sections; casing members carried by said corner-pieces and mounted in the grooves thereof and formed with openings for the admission and outlet of the air the temperature of which is to be changed; bars which support the radiator sections and the ends of which are mounted in said corner-pieces; and supporting members the ends of which are connected with and support the projecting ends of said bars.
